TIRE

James G. Balmer, Jr., Birmingham, Mich., assignor to
United States Rubber Company, New York, N.Y., a
corporation of New Jersey

Filed July 5, 1955, Ser. No. 36,810

Term of patent 14 years

(Cl. D90—20)

Fig. 1

Fig. 1 is a perspective view of a tire embodying my new design, it being understood that the full line portion of the sidewall is repeated throughout the circumference of the tire shown by means of broken lines;

Fig. 2 is an enlarged sectional and fragmentary perspective view of the full line portion of Fig. 1;

Fig. 3 is an enlarged detailed perspective view taken substantially on line III—III of Fig. 2, and

Fig. 4 is an enlarged detailed perspective view taken

substantially on line IV—IV of Fig. 2.

The dominant feature of my design resides in the full line portion of the drawing.

I claim:

The ornamental design for a tire, substantially as shown and described.
